UNITED STATES PATENT OFFICE.

FRANK A. WILCOX, OF ERIE, PENNSYLVANIA.

INNER TUBE FOR PNEUMATIC TIRES.

SPECIFICATION forming part of Letters Patent No. 697,055, dated April 8, 1902.

Application filed February 6, 1902, Serial No. 92,803. (No model.)

To all whom it may concern:

Be it known that I, FRANK A. WILCOX, a citizen of the United States, residing at Erie, in the county of Erie and State of Pennsylvania, have invented certain new and useful Improvements in Inner Tubes for Pneumatic Tires; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to inner tubes for pneumatic tires, and particularly to that class of inner tubes which are used within a sheath or casing in which the terminals of the inner tube are closed and overlap each other in the 20 tire sheath or casing.

The objects of this invention are to effect the economical and permanent closure of the ends or terminals of such inner tubes without the use of molded caps or other additional 25 parts, so that they will effectually prevent the escape of air therefrom and be adapted to overlap and resist rupture when the tubes are inflated in the tire sheath or casing and in use.

30 The features of my improvement are hereinafter set forth and described, and illustrated in the accompanying drawings, in which—

Figure 1 shows a plan view of a section of an inner tube flattened and before the closure is effected. Fig. 2 shows the same, partially in section, with the end thereof folded inward. Fig. 3 shows the same, partially in section, with one side of the inward fold cemented to the 40 inside surface of the tube. Fig. 4 shows the same, partially in section, with the adjacent faces of the inward fold cemented together and the closure completed. Fig. 5 shows a sectional view of the closure of the end of the 45 tube when inflated.

In the drawings illustrating my invention, A indicates a flattened end section of an inner tube, and A' the end portion thereof to be turned back into the tube A in forming the closure of the end thereof. One side a of the end A' of the flattened tube A is prefer-

ably cut away, as illustrated in Fig. 1, so that it is somewhat shorter than the side a'. The inside face B of the side a' is then coated with cement C, after which the end portion A' of the tube is turned back into the inside of the tube A approximately to the dotted line D, which brings the cemented surface B adjacent to the inside surface E of the tube A, as illustrated in Fig. 2. Pressure being then applied, the cement C firmly joins the surface B to the adjacent inside surface E of the tube A, as illustrated in Fig. 3. Cement being then applied to the adjacent faces F F' of the inturned portion A', as shown in Fig. 3, 65 and pressure applied, the faces F F' of the inturned portion A of the tube are firmly joined together, as illustrated in Fig. 4, and the closure of the end of the tube completed, the adjacent faces F F' of the inturned portion A' of the tube being firmly joined together and the surface B of the said inturned part securely joined to the inner surface E of the tube, which completed closure is further illustrated in the inflated section of the 75 tube shown in Fig. 5.

I have described a convenient way of manipulating the tube in making my improved closure; but it is obvious that in making this tube-closure the tube can be manipulated in 80 other ways, if desired. Therefore I do not confine myself to the several steps described in the making of this closure.

Having thus described my invention, so as to enable others to practice the same, what I 85 claim as new, and desire to secure by Letters Patent of the United States, is—

In an inner tube for pneumatic tires, an end closure comprising the end portion thereof turned back into the tube, and one side of 90 the inturned portion of the tube cemented to the inner surface of the tube, and the adjacent faces of said inturned portion of the tube then cemented together, substantially as set forth.

95 In testimony whereof I affix my signature in presence of two witnesses.

FRANK A. WILCOX.

Witnesses:

H. M. STURGEON,
F. J. BASSETT.
